UNITED STATES PATENT OFFICE.

HENRY WILLIAM ROELING, EDWARD HUGH WILLIAMS, AND JOHN GEORGE BAUER,
OF NEW ORLEANS, LOUISIANA.

AUTOMATIC COIN SEPARATING AND COUNTING MACHINE.

1,378,720.

Specification of Letters Patent.

Patented May 17, 1921.

Application filed April 29, 1920. Serial No. 377,641.

To all whom it may concern:

Be it known that we, HENRY WILLIAM ROELING, EDWARD HUGH WILLIAMS, and JOHN GEORGE BAUER, citizens of the United States, and all residing at New Orleans, in the parish of Orleans, State of Louisiana, have invented certain new and useful Improvements in Automatic Coin Separating and Counting Machines; and we do hereby declare the following to a full, clear, and exact description of the invention, such as well enable others skilled in the art to which it appertains to make and use the same.

The present invention relates to improvements in automatic coin separating and counting machines, and has for an object to provide a machine for the expeditious and accurate separation of coins into their various denominations and at the same time causing same to actuate registers by which they may be counted.

It is another object of the invention to provide a machine in which the flow of coins therethrough will be uniform, and therefore not apt to clog with the coins at any particular place, and which will be proof against excessively fast operation.

A further object of the invention lies in providing a simple and inexpensive machine for the separation and counting of coins which will possess an attractive appearance and be capable of effective work.

In the accompanying drawings forming a part of this application, and in which similar reference symbols indicate corresponding parts in the several views:

Figure 1 is a vertical sectional view through an improved separating and counting machine constructed in accordance with the present invention.

Fig. 2 is a similar view taken at right angles to Fig. 1.

Fig. 3 is a fragmentary horizontal sectional view through the machine.

Fig. 4 is a fragmentary perspective view of the kicker shaft.

Fig. 5 is an edge view of the coin trough.

Fig. 6 is a vertical sectional view through the coin distributing drum.

Fig. 7 is an end view of the drum.

Fig. 8 is a cross sectional view therethrough; and

Fig. 9 is a perspective view of the complete machine.

Referring more particularly to the draw-

ings, 1 designates a cabinet having guide rails 2 at the top thereof and preferably at the rear right hand corner to receive a slide 3 which covers the opening to a hopper 4. The hopper 4 lies within the cabinet 1 and has its lower curved end discharging into a tube 5 extending centrally through one head 6 of a coin distributing drum 7. The inner end of the tube 5 enters the lower end of the drum 7, which is supported in an inclined position within the cabinet 1, as shown in Figs. 1 and 6.

The drum is formed with a gear 8 meshing with a pinion 9 on a shaft 10 journaled in suitable bearings in the cabinet, and provided with a two-part clutch 11, 12, and with a handle 13 extending on the exterior of the cabinet for rotation by manual or motive power. The movable element 12 of the clutch is connected to a centrifugal governor 14 which acts to disconnect the clutch should the speed developed by the handle 13 go beyond a predetermined limit. In this way the even and uniform distribution of the coins is assured.

Within the drum 7 are a number of inclined or spiral ribs or rails 15, preferably three in number, which are adapted to engage and lift the coin toward the upper part of the drum 7, wherein is located a partition 16 having a number of slots 17 at its peripheral edge close to the wall of the drum. These slots 17 are also preferably three in number to agree with the number of the ribs 15 employed, the ribs inclining toward the opening 17 and acting to deliver the coins therethrough into the upper compartment of the drum between the partition 16 and the end head 6. In this upper compartment are also placed inclined or spiral ribs or rails 18, of shorter length though greater in number as compared with the first mentioned ribs 15 in the lower portion of the drum.

In the end head 6 of the drum, as shown in Fig. 7, are also provided slots or openings 19, at the peripheral edge thereof close to the drum wall, these slots 19 being preferably twelve in number to agree, for instance, with the twelve ribs 18 in the upper compartment. It will, of course, be understood that the number of these various ribs and openings may be varied as circumstances require, but the object is to insure the uniform delivery and even flow of coins through the

slots 19 in the head 6 to the coin chute 20. As appears in Fig. 1, the upper end of this coin chute is curved and lies very close to the head 6 of the drum so as to receive coins 5 from any part of the same.

A gate or gage plate 21, shown in Figs. 6 and 7, is placed before the head 6 of the drum and is slotted to receive the projecting end of the tube 5. This plate is provided with a slot 22 in which adjustably engages a bolt 23 on a bracket 24 depending from the curved elbow portion of the hopper 4. The plate or gate 24 is therefore vertically adjustable to permit of masking more or less of the slots or openings 19 and regulating to the necessary extent the delivery of coins from the drum to the coin chute 20.

The coin chute is provided with a guide rail 25 along the lower side thereof, the chute being supported in an inclined position, as shown to better advantage in Fig. 2. A gap 26 is made in the guide rail 25 to permit mutilated coins to drop from the chute 20 into a separate compartment 27, thus preventing coins of this kind passing to the slotted portion of the chute to become mingled with the other coins. Any good coins found in the safety compartment 27 30 may be subsequently put through the machine a second time.

The lower portion of the chute is provided with slots 28 of various sizes corresponding to the sizes of the coins of the 35 various denominations, and are such as to permit the coins to become overbalanced and fall therethrough into hoppers 29 provided beneath each of the chutes and communicating with compartments 30 in which 40 the various coins are separately received.

A guide flange 31 is provided along the upper edge of the coin chute 20 at the slotted portion thereof to assist in maintaining the coins in place and to insure the passage 45 of the coins singly therethrough so that they will be properly sorted.

A slot is made near the lower end of each of the hoppers 29; as indicated at 32, and in such slots are placed rotary kickers 33 mounted on a common shaft 34 passing beneath the delivery end of all of the hoppers 29. On the kicker shaft is a sprocket 35 over which runs a chain 36 extending to a second sprocket 37 on a jack shaft 38. 55 Intermeshing gear wheels 39 and 40, respectively, on the jack shaft 38 and a drive shaft 41 provide for the rotation of said jack shaft. The drive shaft 41 also contains a sprocket 42 receiving the lower end 60 of a chain 43, shown in Fig. 1, which is driven from a sprocket 44 on the shaft 10. Of course other means may be resorted to for driving the kicker shaft 34.

The function of the kickers is to engage 65 the ends of the coins in the lower parts of

the hoppers 29 and forcibly eject the same into the compartments 30 and into engagement with the movable tripping parts 45 of registers 46 which total the number of coins passing to the compartments 30. An individual register 46 is provided for each of the compartments to separately total the number of coins of the several denominations. Glass panels 47 may be provided in the front of the cabinet 1 to permit inspection of the registers and the progress of the action of separating the coins.

The coins deposited in the hopper 4 pass through the tube 5 into the lower end of the drum 7 and are engaged by the three 80 ribs 15 which carry the same to the slots 17 in the partition 16 through which the same are delivered to the upper compartment in the drum. Here the coins are again engaged by the ribs 18, which serve to eject 85 the same through the slots 19 and into the coin chute 20. By having the front compartment provided with a greater number of ribs 18, each rib is enabled to deliver a smaller quantity of the coins within a given 90 time as compared to the larger ribs 15, but being more numerous the former ribs 18 act to discharge the coins faster and consequently the movement of the coins to the chute is more even and uniform.

The coins thereupon move down the chute 20 until they arrive at their respective slots 28, whereupon they fall into the particular hopper 29 provided to receive coins of that denomination. Later they are engaged by 100 the kicker 33 and move past the register 46 into the compartment 30. The arrangement of gearing shown is desirable for driving the kicker shaft at a convenient speed for the purpose stated, but we do not restrict 105 ourselves to this particular gearing.

It is obvious that those skilled in the art may vary the details of construction and arrangements of parts without departing from the spirit of our invention, and therefore we do not wish to be limited to such features except as may be required by the claims.

We claim:

1. In an automatic coin separating machine, a receiver for the coins, a chute having means to separate the coins passing therethrough, a rotary drum between the receiver and chute having slots to deliver the coins from the drum, and inclined ribs in 115 the drum for directing the coins through the slots, substantially as described.

2. In an automatic coin separating machine, a coin receiver, a coin chute having means to separate the coins, a rotary drum 125 between the receiver and chute, a partition in the drum separating the same into inner and outer compartments, means to deliver coins from the receiver to the inner compartment, means for transferring the coins 130

from the inner to the outer compartment, and means in the outer compartment whereby the coins may be distributed to the chute in an even stream, substantially as described.

5 3. In an automatic coin separating machine, a receiver, a coin chute having means for separating the coins, a rotary drum placed between the receiver and chute, a partition therein dividing the drum into inner 10 and outer compartments, said partition having slots setting up communication between the compartments, inclined ribs on the drum in the inner compartment leading to the slots, and means in the outer compartment 15 for delivering coins to the chute, substantially as described.

4. In an automatic coin separating machine, a receiver, a coin chute having separating means associated therewith, a rotary 20 drum between the receiver and chute, a partition dividing the drum into inner and outer compartments and having slots therein, inclined ribs in the inner compartment leading to the slots, the outer compartment 25 also having slots leading to the coin chute,

and inclined ribs in the outer compartment leading to the openings therein, substantially as described.

5. In an automatic coin separating and counting machine, a cabinet having an opening in the top thereof, a hopper beneath the opening for receiving coins, a rotary drum in connection with the hopper, means on the exterior of the cabinet to rotate the drum, means for preventing rotation of the drum 30 at excessive speeds, a coin chute in connection with the drum having slots therein, individual hoppers in connection with the slots, a kicker shaft having kickers thereon at the delivery end of the last named hoppers, registers adapted to receive and be actuated by the coins driven through the hoppers by said kickers, gear means to rotate the kicker shaft from the drum rotating mechanism, and individual compartments to 35 receive the sorted coins, substantially as described.

HENRY WILLIAM ROELING.
EDWARD HUGH WILLIAMS.
JOHN GEORGE BAUER.
